Primary Examiner — Jae Liang*Assistant Examiner* — Bryan C Gusman(74) *Attorney, Agent, or Firm* — Sterne, Kessler, Goldstein & Fox P.L.L.C.(57) **CLAIM**

The ornamental design for a table with cabinet as shown and described.

DESCRIPTION

FIG. 1 is a top perspective view of a table with cabinet showing the claimed design;

FIG. 2 is a front view thereof;

FIG. 3 is a rear view thereof;

FIG. 4 is a left side view thereof;

FIG. 5 is a right side view thereof; and,

FIG. 6 is a top view thereof.

The dashed broken lines in the figures show portions of the table with cabinet that form no part of the claimed design.

1 Claim, 4 Drawing Sheets(56)
